UNITED STATES PATENT OFFICE.

EDGAR F. LEEDS, OF MOUNT CARMEL, ILLINOIS.

AIR-SHIP.

No. 879,779.

Specification of Letters Patent.

Patented Feb. 18, 1908.

Application filed July 5, 1907. Serial No. 382,262.

To all whom it may concern:

Be it known that I, EDGAR F. LEEDS, a citizen of the United States, and a resident of Mount Carmel, in the county of Wabash and State of Illinois, have invented new and useful Improvements in Air-Ships, of which the following is a full, clear, and exact description.

This invention is an improvement in air ships, the purpose of which primarily is to provide a construction having a considerable lifting capacity in comparison to the power expended in its operation.

With this object in view I have constructed the ship with a screw or auger which is driven by a suitable means, as an electric motor or turbine engine, and operates preferably as the sole means for lifting and driving the ship in its flight. A car is suspended from one end of the screw, from which the relative direction and inclination of the screw may be controlled by a rudder having a universal connection at the rear end of the ship.

Reference is to be had to the accompanying drawings forming a part of this specification, in which similar characters of reference indicate corresponding parts in all the views.

Figure 1 is a side elevation of the ship complete as it appears in flight; Fig. 2 is a central longitudinal vertical section through the lifting and propelling screw on an enlarged scale; Fig. 3 is a sectional view through the angular frame at the rear of the ship, illustrating the mechanism by which the rudder is controlled; Fig. 4 is a longitudinal sectional view through the car and supporting frame on an enlarged scale; Fig. 5 is an enlarged fragmentary sectional view of the motor and rudder, together with the intermediate connecting mechanism; Fig. 6 is a plan of the rudder, and Fig. 7 is an elevation showing the parts in the positions assumed when the air ship is rising or at rest.

In the construction of my improved air ship, I employ a substantially but lightly constructed screw or auger consisting of a central shaft or spindle 10 concentrically supporting a spiral blade 11 through the intermediary of radiating rods or spokes 12. The blade 11 is preferably removed from the center of the screw immediately surrounding the shaft 10, leaving a central opening therethrough which is closed at the forward end of the screw by a conical cap or hood 13, the same being supported at its center by the

forward extremity of the shaft 10 or other suitable means, and acting to partially overcome atmospherical resistance when the ship is in flight. Said cap or hood 13 also serves to prevent the air compressed by the spiral blade 11 from finding exit at that end, thereby assisting in driving the ship forward.

In order that the air encountered in the revolution of the screw may be enforced to travel throughout its entire length and not be thrown off at the sides, the screw is inclosed by a cylinder or drum 14 of some light material, which is in fixed relation thereto.

Journaled at the rear end of the screw on the shaft 10 is a motor-casing 15, which may inclose either the rotor of an electric motor or the blades of a turbine engine, the same being affixed directly to the shaft 10. In the present instance I have shown the screw driven by an electric motor, which may be operated from any suitable source of electrical supply passing through the conductors 16.

Pivotedly suspended from the motor-casing is a depending bar 17 centrally passing through and affixed to a pyramidal car-frame 18, the latter having a diagonally extending base-bar 19 to which the under face of a car 20 is revolvably supported, as by the hangers 21. Said pyramidal car frame 18 also serves to support the ship when at rest.

A slot 22 formed in the floor of the car longitudinally of the ship receives the lower end of the bar 17 and permits of a limited rocking movement of the car in a longitudinal direction; this rocking movement being preferably controlled by the operation of a hand-wheel 23 which is affixed to a shaft 24 journaled in suitable bearings carried by the bar 17, the shaft being provided with a worm 25 in mesh with a worm-wheel 26, the latter being affixed on a common shaft with a sprocket-wheel 27 which is engaged by a chain 28 attached at its free ends to the opposite sides of the car. It is apparent from this construction that should the car be carried from an approximately horizontal position during the flight of the ship, as by wind pressure, it may be again brought back by swinging the car within the frame.

Attached to the motor-casing in addition to the car is an upwardly projecting angular frame 29 which is rigidly braced and provides bearings for a horizontal and a vertical shaft 30 and 31, respectively. The shaft 30 carries a worm-wheel 32 preferably at one

side of the frame, which is engaged by a worm secured to the upper end of a depending shaft or rod 33, the latter extending within convenient reach of the operator 5 within the car, where it is provided with a hand-wheel or other operating handle 34.

The shaft 31 carries at its lower end a bevel-gear 36 in mesh with a similar gear 37 affixed to a horizontal shaft 38, best shown 10 in Fig. 3. The shaft 38 is journaled in bearings supported from the frame 29 and carries a worm-wheel 39 in mesh with a worm affixed to a depending rod or shaft 40 which also extends within convenient reach of the 15 car 20 where it is provided with a hand-wheel or other operating handle 41.

Near the center, and at the rear side of the frame 29, a socket 42 is secured, which 20 envelops the spherical inner end of a shaft 43, forming the stem of the ship's rudder, the same being composed of two blades 44 and 45, respectively, which intersect each other 25 at substantially right-angles, the blade 44 being connected at the opposite sides of the rudder-stem with cables 46 which are 30 reversely wound about the vertical shaft 31, whereby upon the operation of this shaft by the revolution of the hand-wheel 41, the rudder will be caused to move in a vertical plane about the ball and socket or universal joint as a center.

The blade 45 is attached at the opposite side to the rudder-stem, as shown in Fig. 6, by cables 47 which are reversely wound upon 35 the horizontal shaft 30, and serve to cause the movement of the rudder from side to side through the operation of the hand-wheel 34. If desired, the stem 43 of the rudder may be extended beyond the rear end 40 thereof and connected with the pyramidal car frame 18 by a cable 48, which serves to keep the auger or screw 11 in a vertical position when at rest or to lower it to a horizontal position, and is not used when the air ship 45 is in flight.

The ship as shown and described while being the preferred practical embodiment of my invention, may obviously be variously modified in the details of construction without departing from the nature of my invention as defined in the claims annexed.

Having thus described my invention, I claim as new and desire to secure by Letters Patent:

55 1. In an air ship, a propelling screw, a cylinder in fixed relation to and inclosing the screw, and a car suspended from one end of the screw having means for varying the angular position of the screw and cylinder 60 with respect thereto.

2. In an air ship, a propelling means comprising a driving-shaft, a cylinder surrounding the driving-shaft and rigid therewith, a spiral blade in fixed relation to the cylinder 65 with the portion thereof adjacent to the

driving-shaft being removed, whereby an annular opening surrounding the driving-shaft is provided, and a conical cap at the forward end of the cylinder covering said opening.

3. In an air ship, a propelling screw composed of a central shaft having a spiral blade affixed thereto, a cylinder rigidly secured to and surrounding said blade, a car pivotally suspended from one end of the screw, and means for varying the angular position of the shaft, blade and cylinder with respect to the car.

4. In an air ship, a screw, a frame pivotally supported from the screw, a car pivoted at its bottom within the frame, and means for regulating the relative inclination of the car with respect to the frame.

5. In an air ship, a propelling screw, a motor having a casing journaled at one end of the screw, a pyramidal frame pivotally suspended from the casing, and a car 85 rockingly mounted within the frame.

6. In an air ship, a propelling screw comprising a shaft having a spiral blade affixed thereto with a cylinder rigidly secured to and surrounding said blade, a motor having a casing journaled near one end of said shaft, a frame pivotally suspended from said casing, a car supported within said frame, and means for varying the angular position of 95 said shaft and the blade and cylinder carried thereby with respect to said frame.

7. In an air ship, a propelling screw, a motor including a casing journaled at one end of said screw, a pyramidal frame pivotally suspended from the casing of the motor, and a car supported within the frame, having a limited pivotal movement with respect thereto.

8. In an air ship, a screw, a motor including a casing carried by the screw, a pyramidal frame pivotally suspended from the casing, having a diagonal base-bar, a car pivotally supported on said bar, a flexible connection attached to the opposite sides of said car, and means for operating said connection to tilt the car on said bar.

9. In an air ship, a propelling screw, a bar pivotally suspended from said screw, a pyramidal frame rigidly attached to said bar, a car supported within said frame, having a limited pivotal movement with respect thereto, a flexible connection attached at the opposite sides of the car, and means for operating said connection from the car to tilt it 120 with respect to said frame.

10. In an air ship, a screw, a frame carried at the rear end of said screw, a rudder having a universal connection with said frame, a car pivotally suspended from the 125 screw, and means for moving the rudder in a vertical and in a horizontal plane from said car.

11. In an air ship, a propelling screw, a motor including a casing journaled on said 130

screw, a frame rigidly attached to the motor casing, a rudder composed of two intersecting blades, having a universal connection with said frame, shafts journaled at right-angles to each other in said frame, cables attached at the opposite sides to the blades of the rudder and reversely wound about said shafts, a car pivotally suspended from the motor casing, and means for operating said 10 shafts from the car.

12. In an air ship, a propelling screw, a cylinder surrounding and in fixed relation to said screw, a motor including a casing journaled near one end of the screw, a pyramidal frame pivotally suspended from the casing, a car supported within said frame, having a limited pivotal movement with respect thereto, a rudder supported from the motor casing, means for controlling the rudder from 15 said car, and means for tilting the car with respect to said frame operable therefrom.

13. In an air ship, a propelling screw comprising a central shaft carrying a spiral blade, said blade having a central opening sur-

rounding said shaft, a conical cap covering 25 said opening at the forward end of the screw, a motor including a casing journaled on the rear end of the screw, a frame pivotally suspended from the casing, a car supported within the frame, a rudder supported 30 from the motor casing, and means for controlling the rudder from said car.

14. In an air ship, a propelling screw, a cylinder surrounding said screw, a motor for operating the screw, a rudder supported 35 from the motor, a car pivotally supported from the screw, means for tilting the car relatively to said screw independent of said pivotal support, and means for controlling the rudder from the car.

In testimony whereof I have signed my name to this specification in the presence of two subscribing witnesses.
